UNITED STATES PATENT OFFICE.

GUSTAV J. GRUENDLER, OF ST. LOUIS, MISSOURI.

HINGE.

1,002,391.

Specification of Letters Patent. Patented Sept. 5, 1911.

Application filed December 19, 1910. Serial No. 597,974.

To all whom it may concern:

Be it known that I, GUSTAV J. GRUENDLER, a citizen of the United States, and resident of St. Louis, Missouri, have invented certain new and useful Improvements in Hinges, of which the following is a specification containing a full, clear, and exact description, reference being had to the accompanying drawings, forming a part hereof.

10 My invention relates to improvements in hinges, the object of my invention being to construct a hinge especially designed for the doors of refrigerators and the like, wherein it is necessary to hold the door tightly against the refrigerator around the door opening so as to form a non-leaking joint between the door and the refrigerator as required for the economy of ice and the preservation of a uniform temperature 20 within the refrigerator.

With the above purposes in view my invention consists in certain novel features of construction and arrangement of parts as will be hereinafter more fully described, 25 pointed out in the claims and illustrated by the accompanying drawings, in which—

Figure 1 is a front elevation of a portion of a refrigerator and a portion of a door showing my improved hinge connecting the 30 door to the refrigerator; Fig. 2 is a sectional plan taken on the line 2—2 of Fig. 1; Fig. 3 is a detail perspective of that part of the hinge designed for attachment to the frame of the refrigerator; Fig. 4 is a detail perspective of that part of the hinge to which the strap is pivotally secured and which is carried by the part shown in Fig. 3; and Fig. 5 is a detail perspective of the strap portion of the hinge.

40 Referring by numerals to the accompanying drawing: 1 designates the door frame and 2 the door. Within the frame 1, at a point over which the hinge is to be attached, is an opening 3.

45 4 designates the base portion of that part of the hinge which is carried by the frame 1, having formed integrally therewith the tubular bearing 5 which projects downwardly from the underneath face of the base and is disposed about centrally of the base. This tubular member, when the base is secured in position, occupies the opening 3 in the door frame. Adjacent each corner of the base 4 there is a perforation 6 through 50 which screws are inserted for the securing of the base to the frame 1. Extending up-

wardly from the left hand margin of the base 4 is an integral standard 7 which is grooved throughout its length for the reception of the spring 8, the uppermost end 9 of which extends at approximately right angles to the standard 7. The spring 8 is secured to the standard by means of lag screws 10.

11 designates a substantially U-shaped pintle bearing-member, the leg portions of which are perforated adjacent their ends, and projecting from the body portion of the member is a cylindrical lug 12 which is designed for operation in the tubular member 5 of the base portion. At the outer end of the lug 12 there is a perforation designed to receive the pin 13 for the holding in place of the washer 14, which only serves to prevent the unseating of the member 11 in case the spring 8 breaks.

15 designates the strap or portion of the hinge designed for attachment to the door. Carried by the strap and preferably integrally therewith is the substantially cylindrical pintle bearing-member 16, having the longitudinal rib 17 so that the thickness of the cylinder is increased at a given point, for reasons hereinafter more fully described. The pintle bearing-member 16 is 20 preferably spaced apart from the strap portion proper so that when the door is fully opened the portion 9 of the spring may freely move. Between the frame 1 and the door 2 and preferably carried by the door 25 is a compressible gasket.

Assuming the parts to be assembled, as shown in Figs. 1 and 2, the operation and utility of the hinge will be obvious. However, I desire to call particular attention to 30 some of the advantages of a hinge constructed as shown in the drawings. By reason of the spring 8 and rib 18, it is 35 obvious that the strap portion of the hinge will be forced by the spring in a direction 40 toward the frame 1, thereby holding the door 2 tightly against the frame 1 and in a 45 position to compress the gasket 18. For the reason that the rib 17 has a very slight transverse dimension the spring engages and 50 bears against the strap portion of the hinge only at a very inconsiderable distance, therefore the remainder of the cylindrical portion 55 16 rides freely underneath the portion 9 of the spring. In order to compensate for the 60 variation in the thickness of the gasket, the pintle bearing-member 11 is movable rela-

tive the base 4, the washer 14 being normally a slight distance removed from the lower end of the tubular member 5.

It is obvious a number of changes in the detail construction of my hinge may be made and I do not wish to be understood as limiting myself to the construction shown.

I claim:

1. In a hinge of the class described, a member fixed to the door frame, a member fixed to the door and pivotally connected with the member fixed to the door frame, a sliding connection between the two members so that the member carried by the door may move outwardly and inwardly relative the member secured to the door frame, a spring arranged to act on the member carried by the door when the door is closed, for the purposes stated.
2. In a hinge of the class described, the combination with a hinge member, carried by the door, having a substantially cylindrical-shaped pintle bearing-member, a portion of which bearing is of increased thickness, of a pintle bearing-member secured to the door frame, and a spring acting upon said first mentioned pintle bearing-member and arranged to engage said portion of increased thickness at the time when the door is fully closed, for the purposes stated.

3. In a hinge of the class described, the combination with a member, secured to the door, having a bearing, a portion of which is of increased thickness, of a member secured to the door frame, a spring carried by the member fixed to the door frame, and a second member having a bearing pivotally connected with the bearing of the member connected to the door, which member is loosely mounted upon the member secured to the door frame whereby the member secured to the door is movable relative to said spring.

4. In a hinge of the class described, a member secured to the door frame, a spring carried by said member, a member carried by the member secured to the door frame and capable of lateral movements relative the door frame, a member pivotally secured to said laterally movable member and arranged for engagement with said spring at times, substantially as shown and for the purposes stated.

In testimony whereof, I have signed my name to this specification, in presence of two subscribing witnesses.

GUSTAV J. GRUENDLER.
